UNITED STATES PATENT OFFICE.

FELIX A. FINN, OF NEW YORK, N. Y.

IMPROVEMENT IN STAVE-JOINTING MACHINES.

Specification forming part of Letters Patent No. 42,467, dated April 26, 1864.

To all whom it may concern:

Be it known that I, FELIX A. FINN, of the city, county, and State of New York, have invented certain new and useful Improvements in the Machine for Jointing Staves; and I do hereby declare that the following is a full, clear, and exact description thereof, reference being had to the accompanying drawings, making part of this specification, in which—

Figure 1 is a side elevation, and Fig. 2 a cross vertical section taken at the line A a of Fig. 1.

The same letters indicate like parts in each of the figures.

In the said machine the staves to be jointed are placed one by one on an endless chain-carrier, which carrier is to be formed as to constitute in its length several beds, each to receive a stave, such beds being of a curvature equal to or corresponding with the bilge of the stave when completed, and making part of the intended barrel or cask. As the endless chain-carrier travels along, each stave, with one end inserted under a shoulder or holder on the carrier, passes under a pressure-roller which bends it to the curvature of the bed on which it is placed by the attendant, and, so bent to the required bilge, it is moved along by the continuous motion of the carrier to the action of two inclined circular saws, by which the two joints are cut to the required bevels; and as the endless chain-carrier has several such beds the staves are in succession bent, jointed, and delivered from the machine by a continuous motion of the chain-carrier.

The shafts of the two circular saws are mounted each in a separate swinging frame, and the two frames are mounted on one and the same arbor, on which they can turn, both having the same axis of motion so situated relatively to the plane of motion of the endless chain-carrier that the planes of the two circular saws, when projected, will pass through the axis of the arbor on which the two frames can turn, so that whatever inclination may be given to the two saws to suit various widths of staves the joints cut will always be of the required bevel. The said swinging frames rest on two cams mounted on a cross-shaft, so that by turning the said cam-shaft the attendant can readily adjust the inclination of the saws to any width of stave.

In the accompanying drawings, *a* represents a suitable frame, and *b* an endless chain constituting the carrier. This chain is composed of links *c*, connected together near their lower edges by intermediate links, *d*, which are much thinner than and received in grooves made in the under or inner surface of the links *c*, and project below them. When the chain *b* is straight, the ends of any two of the links *c* will be in contact with each other. This endless chain passes around two polygonal wheels, *e e*, one at each end of the frame. The upper part rests and slides on an upper straight bar, *f*, of the frame, and the upper surface of this bar and the periphery of the two wheels, *e e*, are grooved to receive that part of the intermediate links, *d*, which project below the under surface of the links *c*. The groove in the said bar *f* thus performs the office of guiding the chain in a straight line.

The required motion is given to the endless chain *b* by a driving-shaft, *g*, which carries a worm, *h*, that engages the cogs of a wheel, *i*, on the shaft of one of the wheels, *e*. The chain *b*, as represented, constitutes five beds, *j*, but the number may be changed. Each bed *j* in the proportions represented is composed of six of the links *c*, the links being gradually thicker from each end to the middle, making the upper surface of a convexity similar to the bilge of the stave of the intended barrel or cask; and the first link of each bed (the chain traveling in the direction of the arrow) is formed with a projecting lip, *k*, to receive and hold down one end of a stave.

Above the chain *b* there is a roller, *l*, mounted in a lever, *m*, having its fulcrum in suitable standards, *n*, and by suitable weights or springs applied to the lever the roller *l* is made to press upon and bend the stave into contact with the convex surface of the bed as it is moved along under the roller by the chain.

The two circular saws, *o o*—one on each side of the roller *l*—are mounted each on the inner end of a shaft, *p*, which carries a pulley to receive motion by a belt from some suitable driving-shaft below; and each of the two shafts, *p*, is mounted in a frame, *q*, and the inner ends of the frames are mounted and turn on a fixed arbor, *r*, below the bar *f* of the frame and parallel therewith, so that the two frames can turn on the said arbor. Below the arbor *r*, and at right angles to it, there is a

cross-shaft, *s*, which carries two cams, *t t*, of similar form, so placed that the outer end of each saw-frame will rest on one of the said cams, so that by turning the said cross-shaft *s*, and with it the two cams, the inclination of the two saws can be increased or diminished to suit the width of the staves as they in turn approach the saws. That the attendant may perform this operation readily there is a hand-wheel, *u*, on a longitudinal shaft, *v*, having a worm, *w*; which engages a cog-wheel, *x*, on the cam-shaft.

From the foregoing it will be seen that when the saws are rotating the endless chain-carrier travels with a continuous motion. As each convex bed of the chain approaches the saws the attendant can put a stave onto it by inserting the end of the stave under the lip or shoulder, and the stave will then be drawn under the pressure-roller, bent to the curvature of the bed, and thus bent, passed be-

tween the two saws and jointed, and as one stave is being thus jointed another stave is put onto the next bed, ready to pass in turn to the saws.

For jointing staves which are to be used in making buckets, tubs, churns, and other articles of a tapered form, I contemplate making each bed in the form of a double incline plane, instead of curved, so that each bed will receive two staves, end to end, which will be jointed tapering.

What I claim as my invention, and desire to secure by Letters Patent, is—

The endless chain of beds, substantially as described, in combination with the circular beveling-saws, substantially as and for the purpose set forth.

FELIX A. FINN.
